GEORGE STANFORD WITHAM, JR., OF HUDSON FALLS, NEW YORK, ASSIGNOR TO UNION BAG AND PAPER CORPORATION, A CORPORATION OF NEW JERSEY.

FIBER-CROSSING APPARATUS FOR PAPER-MACHINES.

1,383,363.

Specification of Letters Patent.

Patented July 5, 1921.

Application filed April 14, 1919. Serial No. 289,859.

To all whom it may concern:

Be it known that I, GEORGE S. WITHAM, Jr., a citizen of the United States, residing at Hudson Falls, in the county of Washington, State of New York, have invented certain new and useful Improvements in Fiber-Crossing Apparatus for Paper-Machines; and I do hereby declare the following to be a full, clear, and exact description of the invention, such as will enable others skilled in the art to which it appertains to make and use the same.

This invention relates to fiber-crossing apparatus for paper machines.

In the manufacture of paper intended for bags, wrapping purposes and newspapers, it is highly desirable that there be produced a rugged, tough, flexible sheet that will resist tearing in all directions. Paper produced in accordance with the usual method has not this characteristic for the fibers take up a general direction parallel to each other during the process of formation, so that the resultant product has a grain and may be torn more easily in one direction than in another. Such paper is not suitable for the manufacture of bags and similar articles on account of its liability to tear along the grain, particularly since some of the folds or creases of the bag may run along the grain, thus tending to still further increase the liability to tear. The usual way of attempting to secure a deflecting or crossing of the fibers is to mount a section of the Fourdrinier screen, so that an oscillatory or shaking movement may be imparted to this section of the screen in a direction transverse to its travel. The amount of crossing produced by such arrangements is at best insufficient to give the fibers enough deflection to produce a weave that will resist tearing in one direction as much as in another.

Arrangements depending upon the use of a series of projections or teeth extending into the stream of paper stock have been proposed. These devices are supposed to create a series of small eddies across the flow of the paper stock, thereby giving the fibers a tendency to cross and interlace each other. Such arrangements are usually applied to the paper stock before it reaches the slice bar, so that the stock is supposed to be presented to better advantage to the shaking Fourdrinier screen with the idea that the

felting or crossing action of the latter will be increased. The principal disadvantage of such an arrangement resides in the fact that the teeth dip into the paper stock at a point where there is a comparatively large amount of water in the stock, so that during the further progress of the stock toward the suction boxes, the fibers will tend to become arranged parallel to each other, thereby lessening the effectiveness of the device. If, on the other hand, it be attempted to place the device near the suction boxes where the stock is relatively dry, then the resultant paper will have ridges and depressions, due to the teeth. These and other disadvantages lessen or even destroy the effectiveness of such arrangements, so that they have not been used to any extent.

It is an object of this invention to overcome the disadvantages of prior arrangements for crossing fibers by providing an apparatus in which there is a number of fiber deflecting elements adapted to lie in the stream of the stock obliquely to its direction of travel; these elements being of such a construction that they may be applied to the stock to produce a crossing or interlacing of the fibers at a point so near the zone of action of the suction boxes that the fibers will remain permanently in position, while the elements will not produce ridges or depressions in the stock, even although they enter it at a point just before the drying operation takes place. The apparatus of the invention renders it possible to eliminate the usual arrangement for shaking a section of the Fourdrinier screen so that power may be saved, as well as wear and tear on the machine. The apparatus possesses the further advantage that it will act as a leveler for the paper stock, thus tending to render the paper produced on the machine more uniform in thickness.

The particular nature of the invention, as well as other objects and advantages thereof, will appear more clearly from a description of certain preferred embodiments as shown in the accompanying drawing, in which—

Figure 1 is a side elevation of a portion of a standard paper machine having mounted thereon a modification of the invention employing a dandy roll;

Fig. 2 is an enlarged view in elevation of the adjustable mounting of the device;

Fig. 3 is a plan view of the same;

Fig. 4 is a transverse view in section through the screen and side frames of the paper machine;

5 Fig. 5 is a modified form of the device mounted upon another type of adjusting mechanism;

Fig. 6 is a side view of the mounting of Fig. 5;

10 Fig. 7 is a side view of another form of mounting which carries a device employing spring fingers as the deflecting elements;

Fig. 8 is a plan view of this modification;

Fig. 9 is a transverse view;

15 Fig. 10 is an enlarged view showing the adjustable mounting for the spring fingers;

20 Figs. 11, 12 and 13 are elevation and plan views of a modification in which coils of wire are employed as the deflecting elements; and

Fig. 14 is an elevation of a portion of a paper machine of the cylindrical type with the invention applied thereto.

25 For the purpose of illustrating the application of the invention, only so much of the paper machine is shown as is necessary for a complete understanding of the present improvement. In Fig. 1 the paper machine is of standard construction, having longitudinal side frames 20 between which are mounted carrier rolls 21 for supporting the Fourdrinier screen 23. On each side of the screen is a shake rail 24, these portions of the apparatus being so mounted that an oscillatory movement or "shake" transverse to the direction of travel of the screen may be imparted to the latter, but as the particular mechanism by which this screen may be shaken forms no part of the present invention, and in fact may be eliminated by employing the invention, it will not be described. After passing over the shake portion of the machine, the screen travels over suction boxes 25 of the usual construction.

45 As is customary in all paper machines, there is at each side of the machine a deckle strap 26 running over pulleys 27.

50 In accordance with the embodiment of the invention shown in Figs. 1 to 5, there is mounted on the shake rail 24 on each side of the apparatus, a plate 28 which may be attached by straps 29 and bolts 30, or in any other suitable manner. Upon each plate 28 is a frame 31 hinged at one end, as at 32, to the plate, and at the other end provided with a bracket 33 which engages an adjusting nut 34 upon a vertical screw 35 attached to the other end of the plate. The frame 31 is provided with upstanding end portions 36

60 between which extends a rod 37 and a screw 38 provided with a squared end by which it may be turned by a suitable key. Slidably mounted on the rod 37 and engaging the screw 38 is a block 39 which is provided

65 with a bearing 40 through which passes a shaft 41. It will be understood that the above arrangement is duplicated on the two sides of the machine and between the shafts 41, and extending across the Fourdrinier screen 23 is a dandy roll 42 of any suitable construction, but which, in accordance with the present invention, carries a fiber deflecting element consisting of a helix of wire 43, the convolutions of the helix being separated a sufficient distance to give the required pitch 70 to the coil to produce the deflecting or crossing action upon the fibers of the paper stock. The wire of which the helix is formed should be of such size that when the surface of the dandy roll lies adjacent the top of the 75 layer of paper stock carried by the Fourdrinier screen, the wire will dip into the stock a sufficient distance to produce the deflecting or crossing action of the fibers.

80 For the purpose of rotating the dandy roll, 85 one of the shafts 41 is extended and carries at its end a pulley 44. Each of the upright portions 36 of the corresponding frame 31 is provided with a shaft 45 carrying at its outer end a pulley 46, and one of the shafts is extended as at 47 to carry a driving pulley 48 connected by a belt 49 with a pulley 50 by which power may be transmitted from a moving part of the paper machine. A belt 51 is carried around the pulley 44 and then 90 carried over the end pulleys 46. By virtue of this driving arrangement, the dandy roll may be adjusted back and forth upon the rod 37 by manipulation of the screw 38 and yet may be driven by the belt 51 no matter what 95 position it may occupy with respect to the pulleys 46.

100 In the operation of the embodiment of the invention described above, the dandy roll 42 is adjusted, by means of the nuts 34 and screws 35, so that the face of the roll will be just above the layer of stock upon the Fourdrinier screen, while the wire 43 will dip into the stock. The dandy roll is also adjusted longitudinally of the machine by the screws 38, so 110 that it occupies a position where the most effective deflecting of the fibers takes place. The dandy roll is rotated so that the part adjacent the screen travels with the screen, but it is found in practice that the best results will be secured if the peripheral speed 115 of the dandy roll is somewhat less than that of the screen, so that there is a drag between convolutions of the dandy roll and the stock passing under the roll. The effectiveness of the apparatus depends partly on the mechanical deflecting effect of the wires which lie at an angle to the direction of travel of the fibers, and also upon the ripple or eddy effects produced by the convolutions 120 of wire dipping into the liquid stock and moving longitudinally and transversely thereof; these effects causing the fibers to assume a woven or interlaced relation which will produce a paper having a high tear in 130

all directions, and therefore particularly adapted for use in the manufacture of paper bags, or for wrapping or newspaper.

Instead of using a single helix of wire 5 upon the dandy roll, as shown in the figure described above, the arrangement shown in Fig. 5 may be used, in which an oppositely directed helix 52 is combined with the other one. In order to avoid the irregularities in 10 the contour of the coils which would be produced if the convolutions of the two helices overlapped each other, the wires should be so connected at their points of intersection as to avoid such overlapping. In other words, 15 the points where the wires intersect should be no thicker than the intermediate portions of the wires.

In connection with the dandy roll illustrated in Figs. 5 and 6, there is shown a 20 modified form of adjustable support, but it will be understood that the double helix form of dandy roll shown in Fig. 5 may be used with the form of mounting shown in the preceding figures and vice versa. In the mounting 25 shown in Figs. 5 and 6, there is attached to the shake rail on each side of the machine, by straps or bolts or in any other convenient manner, a plate 53. Hinged to the plate 53 is a bracket 54 having an upwardly bent portion coöperating with an adjusting nut 55 on a vertical screw 56. A bearing 57 is detachably mounted upon the bracket 54, by a bolt and slot connection, or in any other suitable manner, and this bearing 30 carries the shaft 58 of the dandy roll. The shaft 58 at one side of the machine is extended and carries a pulley 59 adapted to be driven from a moving part of the paper machine. The form of mounting just described 35 has not the range of longitudinal adjustment that the mounting shown in the preceding figures possesses, but is useful in cases where no great change in the longitudinal position of the dandy roll is necessary, 40 or if such changes are required the plates 53 may be moved along the shake rail of the machine.

The invention may be embodied in various other forms in which the deflecting elements 50 are not adapted to be moved during the operation of the device and one of these arrangements is shown in Figs. 7 to 10, while another one is shown in Figs. 11, 12 and 13. In the arrangement shown in the first named 55 group of figures, the deflecting elements are in the form of curved Y-shaped spring fingers 60 adapted to dip into the paper stock. The stem portions of these fingers may be clamped between two bars 61 which in turn 60 are attached to a tube 62 adapted to be adjustably retained in a bearing 63 at each side of the apparatus by set screws 64. The bearings 63 are adjustably connected to the inner ends of brackets 65 slidably mounted 65 upon a rod 66 between the ends of a frame

67 attached to the corresponding shake rail of the paper machine. A screw 68 threaded through the bracket enables the latter to be moved along the rod 66 and held in any desired position of longitudinal adjustment. 70

In Figs. 11, 12 and 13 there is shown a modification of the invention in which the deflecting elements consist of a pair of parallel coils 69 extending across the Fourdrinier screen with the convolutions of one 75 coil reversed with respect to those of the other. The coils may be mounted upon semi-circular members 70 which are connected to a transverse bar 71 so that the coils are clamped between the members and the lower 80 face of the bar. The bar 71 is adjustably supported upon brackets 72 by screw connections 73, and the bracket 72 may be mounted upon the shake rail of the paper machine by an arrangement like that shown 85 in Figs. 7, 8 and 9.

In the case of both of the arrangements described above, the deflecting action of the apparatus depends upon fixed elements which dip into the paper stock, instead of 90 upon the action of moving elements as in the case of the dandy roll modification, but it is found in practice that satisfactory results may be attained by the employment of fixed 95 deflecting elements. The dandy roll arrangement is, however, preferred on account of the fact that it exerts a more effective leveling action upon the paper stock and prevents the formation of bubbles on the screen, due to foam produced by sizing conditions, 100 washing conditions, acid in the stock, chemical constituents of the stock and sizing and beating conditions. If such bubbles occur, they are likely to leave bad spots in the paper when they break on the suction box, and it is the usual practice to attempt to eliminate the bubbles by blowing steam or air onto the stock before it reaches the suction boxes. The present invention, 105 particularly in the dandy roll form, serves 110 as a means for breaking up the bubbles. Another advantage of the dandy roll arrangement results from the action of the roll in breaking up any lumps that may be produced in the stock, due to foam or other 115 conditions. These lumps, if they pass over the suction boxes, will break on the couch rolls or on the first press rolls, and result in an imperfect sheet or perhaps even cause a tear in the sheet as it passes over the rolls. 120

As thus far described, the various modifications of the invention have been shown in connection with a paper machine of the Fourdrinier type, but the invention is equally applicable to machines of the cylinder type 125 and in Fig. 14 such an application of the invention has been shown. In this case, the paper machine is of usual construction and need not be described in detail. The fiber deflecting or crossing devices are mounted 130

near the upper part of the cylinders 75. The devices may be in the form of the dandy roll arrangement described above, or they may be in the form of the spring finger or double coil modification. As shown in Fig. 14 they are in the dandy roll form and these rolls 76 are adjustably supported between side frames 77 of the machine and may be driven by a belt 78 from the shaft of the corresponding cylinder 75. On account of the fact that only slight adjustments of the dandy rolls will be required, it will ordinarily not be necessary to provide any belt tighteners or other arrangements to compensate for variations in the distances between the shafts of the cylinders and the shafts of the dandy rolls. The exact position occupied by each dandy roll and the speed at which it travels with respect to the corresponding cylinder will depend upon the characteristics of the paper being produced, but in general the fiber-crossing elements should act upon the stock immediately above the level of the stock in the tanks 79 within which the cylinders revolve.

In the manufacture of paper upon Fourdrinier machines of the ordinary type, it is found that when the shake is taken off that the Mullen test for the paper goes down, but it is found in practice that by employing the apparatus of the present invention, even without the shake, the Mullen test increases even if the paper is of a wild character. This result is due to the crossing of the fibers, so that even thin places in the paper are relatively strong and resist tearing in all directions. In other words, it is found in practice that when the invention is employed, both the tear test and the Mullen test show considerably increased readings, and that one can obtain the same finger or "pop" test both in the normal direction of the grain of the paper and across the grain. It has been found by experiment that paper may be produced in which there is substantially no difference between the tests in either direction, or, if there is a difference, it is slight or hardly perceptible. Such paper is particularly adapted for use in the manufacture of paper bags, for wrapping, for newspaper, or for any other purpose where it is desirable that the paper have substantially the same resistance to tearing in all directions.

55 I claim:

1. A fiber deflecting apparatus for paper machines comprising means lying in the pulp stream at a point whereat a large quantity of the water has been removed and extending obliquely to the direction of travel of the stream for producing a substantially permanent crossing effect upon the fibers as they pass by said means.

2. A fiber deflecting apparatus for paper machines comprising a plurality of fiber de-

flecting elements lying in the pulp stream obliquely to its direction of travel and at a point whereat a large quantity of the water has already been removed.

3. A fiber deflecting apparatus for paper machines comprising fiber deflecting elements lying in the pulp stream at a point whereat a large quantity of the water has already been removed and adapted to move longitudinally and transversely with respect to said stream.

4. In a paper machine having a traveling screen and suction boxes for removing water from paper stock on the screen, the combination of a plurality of fiber deflecting elements lying in the pulp stream slightly in advance of the zone of operation of the suction boxes.

5. In a paper machine having a traveling screen and suction boxes for removing water from paper stock on the screen, the combination of a plurality of fiber deflecting elements lying in the pulp stream slightly in advance of the zone of operation of the suction boxes and extending obliquely to the direction of travel of the paper stock.

6. In a paper machine, a cylindrical member rotatably mounted above the pulp stream and having elements arranged upon its surface in helical, spaced convolutions adapted to enter the pulp stream and produce a crossing effect upon the fibers of stock as they pass under the member.

7. In a paper machine, a cylindrical member rotatably mounted above the pulp stream and having wire wound upon its surface in helical spaced convolutions adapted to enter the pulp stream and produce a crossing effect upon the fibers of stock as they pass under the member.

8. In a paper machine, a dandy roll mounted above the pulp stream and having upon its surface obliquely arranged elements adapted to enter the pulp stream to deflect fibers of stock as they pass under the roll, and means for rotating the dandy roll during the passage of stock thereunder.

9. In a paper machine, a dandy roll mounted above the pulp stream and having upon its surface obliquely arranged elements adapted to enter the pulp stream to deflect fibers of stock as they pass under the roll, means for rotating the dandy roll during the passage of stock thereunder, and means for adjusting the dandy roll vertically and horizontally with respect to the pulp stream.

10. In a paper machine, the combination of plates mounted on the rails of the machine, a frame hinged to each plate at one end, means for raising and lowering the other end of the frame, a rod on the frame, a bearing member mounted on the rod, a screw for moving the bearing member upon the rod, a shaft supported in the bearing member, a dandy roll carried between the

shafts on each side of the machine, fiber deflecting elements mounted upon the dandy roll and adapted to lie in the pulp stream and means for driving the dandy roll while 5 permitting its adjustment longitudinally of the machine by movement of the bearing members upon the rods.

11. In a paper machine, a plurality of curved fiber deflecting elements lying in the 10 pulp stream obliquely to its direction of travel.

12. A method of fiber-crossing in the manufacture of paper comprising crossing the fibers in the pulp stream by means of 15 obliquely positioned deflecting elements at

a point whereat a large quantity of the water has already been removed, to the end that the crossing effected may be substantially permanent.

13. A method of fiber-crossing in the manufacture of paper on a Fourdrinier machine comprising crossing the fibers in the pulp stream by means of obliquely positioned deflecting elements at a point slightly in advance of the zone of operation of the suction boxes, to the end that the crossing effected may be substantially permanent.

In testimony whereof I affix my signature.

GEORGE STANFORD WITHAM, Jr.
